(57) CLAIM

The ornamental design for a server blade, as shown and described.

DESCRIPTION

FIG. 1 is a top, front and right side perspective view of a server blade in accordance with our design;
FIG. 2 is a right side elevational view thereof;
FIG. 3 is a left side elevational view thereof;
FIG. 4 is a front elevational view thereof;
FIG. 5 is a back elevational view thereof;
FIG. 6 is a top plan view thereof; and,
FIG. 7 is a bottom plan view thereof.

The components that are depicted in broken lines are for illustrative purposes only and form no part of the claimed design.
